Des. 241,957
Patented Oct. 19, 1976

241,957

GOLF PUTTER

B. J. Melton, 2415 Grandview, Richardson, Tex. 75080

Filed Feb. 7, 1975, Ser. No. 547,799

Term of patent 14 years

Int. Cl. D21—01

U.S. Cl. D34—5 GC

FIG. 1 is a front view of a golf putter showing my new design;

FIG. 2 is a side view thereof;

FIG. 3 is an enlarged top view of the putter head;

FIG. 4 is an enlarged view of the face of the putter head;

FIG. 5 is an enlarged view of the rear of the putter head; and

FIG. 6 is a front view of the putter head.

I claim:

The ornamental design for a golf putter, as shown.
